UNITED STATES PATENT OFFICE.

MARY W. STROM, OF BESSEMER, MICHIGAN.

YARN REEL.

Application filed January 23, 1924. Serial No. 387,973.

To all whom it may concern:

Be it known that I, MARY W. STROM, a citizen of the United States, residing at Bessemer, in the county of Gogebic and State of Michigan, have invented new and useful Improvements in Yarn Reels, of which the following is a specification.

This invention relates to knitting and more particularly to a yarn reel.

10 The primary object of this invention resides in providing a substitute for the card commonly used to support a skein of yarn while knitting.

15 Another object of this invention resides in the provision of a rotatable yarn reel, for a skein of yarn, adapted to be removably secured to a stationary support.

20 A still further object of this invention resides in the provision of a rotatable yarn reel of such construction that it can be adjusted to accommodate skeins of yarn of different lengths.

25 In addition to the aforesaid objects, this invention resides in an embodiment of elements adapted to cooperation in providing a yarn reel capable of stretching a skein of yarn to the proper limitations of its convolutions.

30 Aside from the above referred to objects, this invention resides in providing a rotatable, adjustable yarn reel that can readily be collapsed in a compact condition for storage.

35 With these and other objects in view, this invention resides in certain novel features of construction, arrangement and combination of elements to be hereinafter more particularly set forth in the specification, illustrated in the accompanying drawings and 40 pointed out in the appended claim.

In the accompanying drawings forming a part of this application,

45 Fig. 1 is a plan view of a yarn reel as constructed in accordance with this invention.

Fig. 2 is a side view thereof.

Fig. 3 is a sectional view approximately on line 3-3 of Fig. 1.

50 Fig. 4 is a detail sectional view on line 4-4 of Fig. 2.

Fig. 5 is a detail end view of one of the adjustable arms of the yarn reel showing a pair of links associated therewith.

Fig. 6 is a plan view thereof.

55 In the present embodiment of this in-

vention the numeral 5 designates a standard having a rotatable ring 6 secured at one end thereof and a slidable ring 7 disposed for adjustment toward and from the first mentioned ring.

These rings are provided with peripheral slots 8 for the reception of the inner ends of extensible arms 9 and, through the instrumentality of pivotal elements 10, the arms can be extended or retracted by moving the adjustable ring 7 along the standard 5.

Loosely connected to the outer ends of the extensible arms 9 by flexible elements 11 are crossed links 12 which, through their particular relation with the extensible arms 9, form broad resting points for the convolutions of yarn as they are wound thereon. Through the instrumentality of the flexible elements 11, the cross links 12 have freedom 70 of action at their ends so as to allow the contacting areas thereof to twist the cross links, during their extension, in such positions that their broad sides will be presented for receiving the yarn and the possibility of the yarn being wedged between the cross links obviated. This particular manner of suspending the cross links 12 also allows the same to compensate for any 75 undue pressure brought thereagainst while winding the yarn thereon, particularly for the reason that they will yield at their points of suspension.

In order to retain the extensible arms 9 in any desired position, or in fact such position as will suit the particular skein of yarn to be retained on the reel, the standard 5 is provided with a series of apertures 13 adapted to accommodate a pin 14 bearing against the slidable ring 7. This pin 14 90 is preferably secured to the standard 5 by a flexible element 15 to prevent its being misplaced or lost.

Carried by the standard 5 in any suitable position thereon is a clamp 16 which 100 is adapted to rigidly support the standard and its associated elements in such position that the yarn on the reel can be unwound therefrom to suit the conditions under which an individual desires to work.

With this invention fully set forth, it is manifest that a yarn reel has been produced which will respond to all the requirements necessary in retaining a skein of yarn in proper condition for knitting 110

and, through the association of elements thus employed, the device can be manufactured at a reasonable cost.

Having thus described my invention 5 what I claim and desire to protect by Letters Patent is:

A yarn reel of the character set forth, the combination of a ring, a standard rotatably supporting the ring, extensible arms 10 pivotally connected at their inner ends to the ring, a slidable ring carried by the

standard, extensible arms pivotally connected to the first mentioned arms at their medial portions, loop-shaped cords carried at the extremities of the arms, crossed links 15 suspended at their extremities by the loop-shaped cords and means retaining the slidable ring in adjusted position on the standard.

In testimony whereof I affix my signature.

MARY W. STROM.
